SCREW DRIVER

Donald C. Thomson, Dayton, and Moses A. Moers,
Cincinnati, Ohio

Application July 27, 1943, Serial No. 496,316

1 Claim. (Cl. 240—6.46)

This invention relates to a screw driver, and has for the primary object the provision of a device of this character which is provided with a self-contained electric illuminating means manually and easily controlled for illuminating the bit of the device as well as the screw to be turned thereby which will greatly assist the user of the device in bringing the bit into engagement with the screw when the latter is obscured by darkness.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawing, in which

Figure 1 is a side elevation, partly in section, illustrating a screw driver constructed in accordance with our invention.

Figure 2 is a fragmentary sectional view showing the manually operated switch for controlling the illuminating means.

Figure 3 is a sectional view taken on the line 3—3 of Figure 1.

Referring in detail to the drawing, the numeral 5 indicates the handle of the device and which is provided with a chamber 6 opening outwardly through one end of said handle and normally closed by a cap 7 threaded onto the handle. A portion of the handle is reduced to form a shank 8 socketed to receive a bit 9 of the screw driver. The bit has the conventional type of end 10 to engage a kerf of a screw or similar device.

The shank 8 is formed with flutes extending substantially the full length thereof and which flutes assist in preventing the bit from turning relative to the handle. It is to be understood that when the bit is arranged in the handle the flutes are embedded therein.

The handle 5 is constructed of a durable transparent plastic and is covered with an opaque coating except for the end of the reduced portion 8 which remains transparent to permit light rays from within the handle or chamber 6 thereof to shine on the bit 9 and follow along the latter to the end 10, efficiently illuminating said end as well as the screw to be engaged thereby. The flutes on the bit act in guiding the light rays to the end 10.

The cap 7 is of a non-transparent material, also preferably plastic.

An electric lamp 11 is arranged within the

inner end of the chamber 6 and is supported by an electric lamp socket 12 forming an integral part of a metallic frame or holder 13. The frame 13 includes parallel portions 14, one of which is of greater length than the other and both provided with spring grip portions 15 forming integral parts thereof. The longest portion 14 is composed of separable sections connected together by an insulating strip 16 and one of said sections has an angularly related end portion 17.

When the frame 13 is removed from the chamber an electric dry cell of a conventional construction may be readily inserted therein and firmly gripped by the spring fingers 15 and the end portion 17 of the frame. The dry cell is indicated by the character 18 and its contact 19 engages with the spaced contacts of the electric lamp 11. It is to be understood that the dry cell 18 has the usual insulating cover preventing the frame from forming an electrical contact with the dry cell except through the end portion 17 which contacts one end of the dry cell.

The cap 7 is provided with a seat or socket 19' to receive a coil spring 18' bearing against the portion 17 of the frame to hold the same in tight contact with the dry cell. The spring 18' also acts to hold the electric lamp 11 tightly against the inner end wall of the chamber 6 and prevents the dry cell as well as the frame from moving accidentally within the chamber.

The handle 5 is provided with a slot 20 through which a shank 21 of a finger piece 22 extends for a limited sliding movement. A spring contact 23 is secured to the shank 21 and operates therewith within the chamber and one end portion thereof is curved, as shown at 24, while the other end portion thereof has a compound curvature, as shown at 25. Shoulders 26 are formed on the wall chamber and are spaced an equal distance from the slot 20 of the handle and are engaged by the contact, so that when the finger piece 22 is slid in one direction they will cause the curved portions of the contact to engage the sections of the longest portion 14 of the frame and thereby complete the electric circuit between the electric lamp and the dry cell. When the finger piece 22 is slid in an opposite direction, the curved portions of the contact ride off of the shoulders thereby disengaging the contact from the frame breaking the circuit between the dry cell and the electric lamp. The shoulders 26 operating in conjunction with the spring contact prevents the same from accidentally shifting its positions as will be apparent by referring to Figure 2.

In use, the operator moves the finger piece 22

to complete the electric circuit between the dry cell and the electric lamp and the illuminating rays from the electric lamp escape at the end of the handle carrying the bit 9 and follow the flutes of the bit to the end 10 thereof, so that said end will be efficiently illuminated as well as the screw when the end 10 is brought in the vicinity of the screw consequently assisting the operator in engaging the end 10 of the bit with the screw when the latter is obscured by darkness.

When the use of the screw driver is no longer desired, the operator moves the finger piece 22 to interrupt the circuit between the dry cell and the electric lamp.

While we have shown and described the preferred embodiment of our invention, it will be understood that minor changes in construction, combination and arrangement of parts may be made without departing from the spirit and scope of the invention as claimed.

Having thus described the invention, what we claim is:

In a screw driver, a handle having a trans-

parent end and provided with a chamber, a frame located in the chamber and removable therefrom and including a sectional portion connected by an insulating strip, a dry cell mounted in the frame and electrically connected to one of the sections, an electric lamp socket carried by the frame, an electric lamp carried by the socket and electrically connected to the dry cell, a cap for closing the chamber, tension means between the cap and the frame, spring ears on the frame to grip the dry cell, shoulders formed on the handle within the chamber, said handle having a slot between the shoulders, a shank slidable in the slot including a finger piece arranged exteriorly of the handle, and a spring contact carried by the shank and including curved end portions to ride the shoulders and to be engaged and disengaged with the sections of the frame by the sliding movement of the finger piece in opposite directions to close and open the electric circuit between the dry cell and the electric lamp.
